UNITED STATES PATENT OFFICE.

ALBERT J. TOWNSEND AND HERBERT W. SNYDER, OF LIMA, OHIO.

LOCOMOTIVE DRAFT APPLIANCE.

Application filed February 4, 1922. Serial No. 534,155.

To all whom it may concern:

Be it known that we, ALBERT J. TOWNSEND and HERBERT W. SNYDER, citizens of the United States, both residing at Lima, 5 in the county of Allen and State of Ohio, United States of America, have invented certain new and useful Improvements in Locomotive Draft Appliances, of which the following is a specification.

10 This invention relates to draft appliances and is particularly useful in connection with steam railroad locomotives.

In standard locomotive practice, a stationary nozzle is employed, the area through 15 which the steam is discharged being constant so that the pressure required to force the exhaust steam through the nozzle—commonly called the back pressure—bears a certain relation to the amount of steam being 20 discharged. Such back pressure is low when a small amount of steam is being discharged through the nozzle, and correspondingly higher when larger amounts of steam are being used. Back pressures of 25 material amount are undesirable as they subtract from the power developed by the cylinders. Heretofore, various designs of variable nozzles have been made, such variable nozzles being operated, for the 30 most part, by manual means so that the area of the nozzle may be altered as required in accordance with the amount of steam being used, in order to maintain the back pressure within reasonable limits. The manually 35 operated variable nozzles, however, have not gone into use for the reason that their usefulness is comparatively negligible unless they are substantially constantly being manipulated, for unless this were done the proper area of nozzle would only be approximated. For practical considerations, 40 it is impossible to properly manipulate the nozzles manually.

It is the purpose of our invention to provide an improved variable exhaust nozzle, the operation of which is entirely automatic and in accord with the quantities of steam being passed through the cylinders, that is to say, the nozzle is operated in such manner as to maintain the desired ratio of nozzle area to the amount of steam being used, thereby permitting a suitable regulation of the back pressure.

One of the primary objects of our inven-

tion, therefore, is to provide a simple and 55 effective variable exhaust nozzle having the characteristics and advantages described.

We accomplish the foregoing by means of a construction, the preferred embodiments of which, are illustrated in the accompanying drawings, wherein:

Fig. 1 is a diagrammatic side elevation of a locomotive, illustrating the application of our invention thereto; Fig. 2 is an enlarged side elevation and partial section, 65 illustrating the working parts of our improvement; Fig. 3 is a partial end elevation and section of Fig. 2.

Our invention is based on the fact that there is a certain drop in steam pressure 70 between the boiler and the cylinders, and this drop in pressure bears a definite relation to the amount of steam being used. The steam, after leaving the throttle, has to pass through the different steam pipes 75 to the cylinders, and, the area of these pipes being constant, it follows that a certain amount of pressure is utilized in forcing the steam through the pipes, the amount of this pressure increasing as more steam 80 has to be forced through the pipes. Thus, while the pressure at the throttle will be maintained, the steam pipe pressure at the cylinders will be less, the difference being 85 in proportion of the amount of steam passing through.

For the purposes of this specification, we have illustrated a variable nozzle device A which, in the position shown in Fig. 2, provides a nozzle area of the size requisite 90 to secure proper draft when the engine is using comparatively small quantities of steam. The nozzle area is increased by moving the member 7 downwardly, which has the effect of creating a space between such 95 member and the outer member 8. By virtue of the taper of the members 7 and 8, a relatively small amount of vertical movement of the member 7 will provide sufficient additional nozzle opening to meet the requirements throughout the range of operating conditions.

For operating the member 7 of the variable nozzle device, we provide the following mechanism: The reference numeral 9 denotes an operating cylinder preferably secured to the smoke box shell in the manner indicated in Figs. 2 and 3. Working in this

cylinder is a piston 10, the piston rod 11 of which is connected to the crank 12 by means of a link 13 and stem 13^a. The crank 12 is fastened to a shaft 14 extending inwardly 5 into the smoke box and being provided at its inner end with a second crank 15 which in turn operates the stem 16, the upper end of which carries the member 7. Upward movement of the piston 10 from the position indicated in Fig. 2 imparts a downward movement to the member 7, increasing the area of the nozzle opening. The piston 10 is normally held in the position of Fig. 2 by means of the regulating spring 17, the 10 compression of which is adjusted by means of the nut 18. This nut is locked by a lock nut 19. To prevent the spring from jamming the member 7 against the member 8, a stop 20 is provided at the lower end of the 15 piston rod. This stop limits the downward movement of the piston and its rod.

When the engine is working, pressure at the throttle is transmitted to the lower part of the cylinder by means of the pipe 21 and 20 the steam pipe pressure is transmitted to the upper part of the cylinder by means of the pipe 22, the difference in these pressures placing an unequal load on the piston, forcing it upward against the compression of 25 the spring. Since the rate of compression of the spring does not change, the motion of the piston is proportional to the difference in the pressure. Thus when the engine is only using a small amount of steam, the 30 drop in pressure through the steam pipes is small, and the piston moves upward but a slight distance. As more steam is used by the locomotive, the drop in pressure increases and the piston moves up farther, the motion 35 being transmitted to the member 7 through the operating connections described. The area of the nozzle is thus kept at the proper size for the amount of steam which is being discharged. By adjusting the spring 17, the 40 ratio of the nozzle area to the amount of steam can be regulated so as to produce whatever back pressure is required to furnish adequate draft. Thus excessive back pressure is eliminated. At the same time the 45 mechanism can be altered so that it may be accommodated to different types of locomotives, different classes of service, and differ-

ent kinds of fuel or variations in quality of fuel.

We claim:

1. The combination in a steam locomotive, of a variable exhaust nozzle and means for operating the same controlled by the drop in steam pressure between the boiler and the cylinders.

2. The combination in a steam locomotive, of a variable exhaust nozzle, and means for operating the same responsive to conditions in the steam line between the boiler and the cylinders.

3. The combination in a steam locomotive, of a variable exhaust nozzle, and means for regulating the opening thereof as the locomotive is being operated, said means being automatically responsive to the variations in pressure conditions in the steam line to the cylinders as determined by the amount of steam being used.

4. The combination in a steam locomotive, of a variable exhaust nozzle, and means for progressively adjusting the opening thereof as the locomotive is being operated, said means being automatically responsive to the variations in pressure conditions in the steam line to the cylinders as determined by the amount of steam being used.

5. The combination in a steam locomotive, of a variable exhaust nozzle and means for operating the same controlled by the drop in steam pressure between the boiler and the cylinders including a piston subjected on one side to substantially boiler pressure and on the other side to substantially cylinder pressure.

6. The combination in a steam locomotive, of a variable exhaust nozzle and means for operating the same controlled by the drop in steam pressure between the boiler and the cylinders including a piston subjected on one side to substantially boiler pressure and on the other side to substantially cylinder pressure, and a spring yieldingly holding the piston in the position securing small nozzle opening.

In testimony whereof, we have hereunto signed our names.

ALBERT J. TOWNSEND.
HERBERT W. SNYDER.
